CLAIM

The ornamental design for a six-pack bottle carrier with graspable loops, as shown and described.

DESCRIPTION

FIG. 1 is a top front perspective view of an ornamental design for a six-pack bottle carrier with graspable loops according to the present invention.

FIG. 2 is a bottom rear perspective view thereof.

FIG. 3 is a top view thereof.

FIG. 4 is a front view thereof, additionally illustrating in dashed lines bottles secured within the six-pack bottle carrier with graspable loops, the back side being a mirror image thereof.

FIG. 5 is a right side view thereof, additionally illustrating in dashed lines bottles secured within the six-pack bottle carrier with graspable loops, the left side being a mirror image thereof.

FIG. 6 is a right side view thereof, additionally illustrating in dashed lines a hand lifting the six-pack bottle carrier with graspable loops by the graspable loops, as well bottles secured within the six-pack bottle carrier with graspable loops; and,

FIG. 7 is a bottom view thereof.

Dashed lines in FIG. 4 and FIG. 5 illustrate environment in the form of bottles secured within rings of the six-pack bottle carrier with graspable loops. The dashed lines illustrating the bottles in FIG. 4 and FIG. 5 form no part of the claimed design. Additional dashed lines in FIG. 6 illustrate environment in the form of a hand shown grasping loops of the six-pack bottle carrier with graspable loops, and bottles secured within rings of the six-pack bottle carrier with graspable loops. The dashed lines illustrating the hand and bottles in FIG. 5A also form no part of the claimed design.
